ROAD MACHINE

George P. Green, Lubbock, Tex.

Application March 3, 1945, Serial No. 580,882

14 Claims. (Cl. 94—44)

1

This invention relates to an improvement in road machines, and the principal object is to provide a machine of this class which may be advantageously applied in construction operations relative to road subgrades, base courses, surface courses and other work of similar nature such as terracing, leveling, compacting and miscellaneous construction of this nature. These and other objects are hereinafter more fully described, illustrated in the drawings, and specifically pointed out in the appended claims; it being understood that construction deviations may be made so long as they fall within the scope of the claims.

Figure 1 is an elevation of the right side of the machine.

Fig. 2 is a rear elevation of the left end of the machine (Fig. 1).

Fig. 3 is a rear elevation of the center portion of the machine.

Fig. 4 is an enlarged plan view of the portion of the machine shown in Fig. 2.

Fig. 5 is a plan view of the portion of the machine shown in Fig. 3.

Fig. 6 is a sectional elevation of a front portion of the carriage assembly.

Fig. 7 is a transverse section along lines 7—7' and 7—7" of Fig. 6.

Fig. 8 is a sectional view of a mixer claw along line 8—8, Fig. 7.

Fig. 9 is a section through the mixer shaft along line 9—9, Fig. 6.

Fig. 10 is a section through the mixer shaft along line 10—10, Fig. 6.

Fig. 11 is an elevation, partly in section, through the rear part of the carriage assembly.

Fig. 12 is an elevation, partly in section, taken transversely of the portion shown in Fig. 11 along line 12—12 (Fig. 11).

Fig. 13 is a section of a portion of the rail rollers of carriage support member 37 of Fig. 11.

Fig. 14 is a plan view of the scarifier along line 14—14, Fig. 6.

Fig. 15 is an elevation, partly in section, through blade assembly taken along line 15—15, Fig. 6.

Fig. 16 is a section of the reel member, shown in Fig. 1.

Fig. 17 is a sectional elevation through the transmission taken along line 17—17, Fig. 5.

Fig. 18 is a section through the shift control, along line 18—18, Fig. 17.

Fig. 19 is an elevational view of an hydraulic control for the steering arrangement.

Fig. 20 is a vertical section along line 20—20, Fig. 19.

2

Fig. 21 is a front elevation, partly in section, of a portion at the front wheel of the machine.

Fig. 22 is a section through an hydraulic grade control mechanism, along line 22—22, Fig. 21.

Fig. 23 is an elevational view of an hydraulic grade control mechanism, along line 23—23, Fig. 22; and

Fig. 24 is an elevational view, partly in section, of a clutch for driving and steering the machine, shown in Fig. 2.

Similar numerals refer to similar parts throughout the several views.

In general, the machine comprises a horizontal frame provided with supporting wheels at each end, to travel along a strip of work, with the roadworking structure spanned transversely thereto; and a carriage frame roller mounted on the structure and supporting certain members such as a mixer, blades and rollers adapted to perform a sequence of road construction operations as the carriage is propelled back and forth across the work. The travel rate of the entire machine along the strip of work is coordinated with the carriage travel, so that the operations lap to produce a uniformly worked section.

The structure which spans the work comprises two I beams, 1 and 2, Figs. 1 to 5, which are hinged at the middle on hinges 3, Figs. 1 and 5. The I beams are spaced and secured horizontally by the braces 4, Figs. 4 and 5. The I beams are pivoted about hinges 3 by means of shaft 5, Figs. 1 and 5, with eccentric portions connecting integral truss portions 6 of the beams through links 7, Figs. 3 and 5. A crank 8 with a worm gear cooperates with gear 9 which is adapted to rotate shaft 5 and thus enable adjustment of the angle at which beams 1 and 2 meet at hinges 3. This is for the purpose of predetermining the crown of the road section under construction or repair.

The span structure is detachably fixed to girders 10, and braces 15, Figs. 1 and 4, by bolts (not shown) passing through holes in the contacting flanges of the members, the bolt holes being arranged along the I beams to permit fixing the girders 10 at optional positions to thus adapt the wheel tread to various widths, as well as to facilitate knock-down for transportation. Girders 10 are supported by a wheel arrangement on each end adapted to support the entire machine.

The rear wheels 11, Figs. 1, 2 and 4, are relatively wide for bearing and traction purposes. Axle 12 for wheel 11 is rotatably mounted in bearings 13 on frame members 14, Figs. 1 and 2, which are fixed to girders 10. Braces 15 connect frame

members 14 to beam 2 and are fixed to girders 10 by means of webs 16, Fig. 2. A sprocket 17, Fig. 1, is fixed to each wheel 11 and cooperates with chain 18 to which power is transmitted to propel the machine.

Pneumatic front wheels 19, Figs. 1 and 21, are rotatably fixed to respective forks 20 from which a piston 21 extends into a cooperating hydraulic cylinder 22 (Fig. 21). A link 23, Fig. 1, fixed to front wheel fork 20 is adapted to be fixed at option to a bracket 24 which is rigidly fixed to cylinder 22 so that piston 21 is free for longitudinal motion and restrained from rotation in the cylinder 22.

The carriage which supports the various road operation performing members comprises a frame consisting of main members 25, Fig. 1, with cross braces 26, 27 and 28, Fig. 11. Strap-like cross braces 29, Fig. 11, may be placed diagonally on the frame. The carriage frame is pivotally fixed to an intermediate frame by bearing member 30, Fig. 11, on the carriage frame connected to bearing member 31 of the intermediate frame by pin 32.

The intermediate frame consists of cross members 33 (Fig. 11), longitudinal members 34 (Fig. 1), and diagonal members 35 (Figs. 11 and 12). The intermediate frame has two roller supporting members 36 (Figs. 1 and 11) fixed to the back, and two members 37 fixed to the front as shown in Figs. 11 and 12. Rail rollers 38 are arranged on supports 36 and 37 in a manner to roll on beams 1 and 2 with fixed rail portions 39 as shown in Figs. 11 and 13. The pivoting of the carriage frame about pin 32 is maintained in a plane with the intermediate frame by means of cross member 28 of the carriage frame being slidably retained between intermediate frame member 33 and plates 40 which are secured to support members 37 by bolts 41, Figs. 11 and 12.

The range of the sliding motion and related pivoting of the carriage frame relative to the intermediate frame is limited by stop screws 42 and 43, Fig. 12, which are oppositely threaded through the respective support members 37, and operated by a nut and spline member 44. Rubber cushioned pads 45, Fig. 12, fixed on members 25 at each side of the carriage frame serve as stop contacts for screws 42 and 43. The purpose of this arrangement, whereby the angle at which the carriage frame may pivot relative to the intermediate frame may be predetermined by adjusting screws 42 and 43, is to position the carriage frame at right angles to its path of travel over the work, for reasons hereinafter set forth.

The carriage frame, members 25 etc., with the attached operation members and the intermediate frame are propelled back and forth along beams 1 and 2 of the span structure, by means of cable 46 which is attached to each support member 37 by means of eye bolts 47, Fig. 11. Cable 46 passes over a sheave 48 (Figs. 1, 4 and 5) at each end of the span structure and over drum 49 (Figs. 1 and 17) which actuates the cable. Preferably the cable is fixed to the drum to prevent slippage and sufficient raps are made over the drum each side of the fixed point to permit sufficient drum rotation either way for the back and forth travel of the cable. Drum 49 is actuated by a power plant 50, Figs. 1 and 5, through a transmission 51 adapted to automatically reverse the direction of rotation of drum 49 at a predetermined instant.

Details of the transmission 51 and drum 49 are shown in Figs. 17 and 18. An end member 52 is fixed to drum 49 by bolts 53 and rotatably

supported by a ball bearing on spindle 54 which is supported by member 55, Figs. 17 and 1. End member 52 has a cam shaped section which fits concentrically along the interior cylindrical section of a piston member 56 (Fig. 17). Piston 56 is arranged to rotate with shaft 57 by means of a slideable splined section, and is adapted for longitudinal and rotary motion in the cylindrical portion of drum 49 which maintains therewith a fluidtight contact. Piston 56 is yieldably maintained in contact with the cam portion of end 52 by means of spring 58 which is maintained and adjusted in compression by a member 59 threaded into a portion of drum 49 and adapted to serve as a bearing and packing on shaft 57. A valve 60 is adapted to permit unobstructed passage of fluid from the top to the bottom of piston 56. A passage 61 is provided through piston 56 of correct size to permit return of fluid to the top of the piston 56 at a rate to prevent rapid downward movement of the piston.

The mechanism is operated with piston 56 submerged in a suitable fluid. The purpose of this arrangement within drum 49 is to provide a cushion between the rotation of shaft 57 and the drum 49 when a sudden impact load is applied. Spring 58 applies sufficient force on piston 56 to cause the piston to return to its lowermost position with the cam sections meshed, i. e., when the overload due to impact is reduced to a normal load, the rate of return being restricted by the rate at which fluid passes from the bottom to the top of piston 56. The restriction on the rate of fluid flow through passage 61 is in amount that is necessary to prevent harmonic variation in the rotation rate. Under normal operating conditions, including the rotation reversal of drum 49, the rotative displacement of the drum 49 relative to shaft 57 is small, the impact being absorbed by the rubber cushioned pad 45 on the carriage frame.

In the transmission (Fig. 17) a shaft 62 is rotatably supported by bearings 63 and 64 which are fixed to transmission box 51, and transmits power from plant 50 through gears 65 and 66 which are splined to rotate with shaft 62. A shift control 83A (similar to 83B shown in Fig. 18) may be of the usual thrust and collar arrangement, and cooperates with gears 65 and 66 to shift and maintain their position on shaft 62. The gears are shown in a neutral position in Fig. 17. When they are shifted to the left, Fig. 17, gear 65 meshes with a reverse gear 67 which cooperates with gear 68 fixed to a shaft 69 with gears 70, 71 and 72. Shaft 69 is rotatably supported by bearings 73 and 74 which are fixed to the transmission box 51. Gear 65 may be shifted to mesh with gear 70, or gear 66 to mesh with gear 71 to actuate shaft 69 at two respective speed ratios. Gear 72 cooperates with gear 75 to actuate shaft 76 which is rotatably supported by bearings 77 and 78. Gears 79 and 80 are rotatably supported on shaft 76 and each mesh with gear 81 which is fixed to shaft 57. A clutch member 82 is splined to rotate with shaft 76 to engage matching clutch portions of either gear 79 or 80 at option.

Clutch member 82 is shifted by a control as shown in Fig. 18. An arm 83, fixed to shaft 84 which is rotatably supported by box 51, is actuated by lever 85. Lugs 86 are provided to engage a grooved section of clutch member 82 in a manner to control its position longitudinally along shaft 76. Spring 87 is arranged in compression between a portion of arm 83B and box 51 with

dead center at neutral shift position, and serves to facilitate engaging the clutch. A wing screw 88 is provided to fix lever 85 in neutral or other positions. A roller bearing 89 and packing 90, Fig. 17, are provided for drum shaft 57.

The remainder of the transmission mechanism relates to means for propelling the entire machine along the work by wheels 11, Fig. 1. Gear 91 (Fig. 17) which is an integral portion of shaft 76, cooperates with gear 92 to rotate shaft 93 and gear 94. Shaft 93 is rotatably supported by bearings at each end which are fixed to portions of transmission box 51. Shaft 95 is rotatably supported by gear 91 and bearing 96 (Fig. 17). Gear 97 is arranged to rotate shaft 95 by means of splines adapted to permit shifting the gear along the shaft to mesh gear 97 with either gear 91 or 94 at option to thus provide two different speeds. A control arm 83C similar to arm 83B in Fig. 18, cooperates with gear 97 to control its position along shaft 95. Gear 97 is shown in a neutral position in Fig. 17. Worm gear 98 is fixed to shaft 95 and cooperates with gear 99 to rotate shaft 100. Shaft 100 is rotatably supported by transmission box 51 and extends exterior thereof and through beam 2 of the span structure where it is rotatably supported by bearing 101 as shown in Fig. 1.

Gear 102 is fixed to the end of shaft 100 and operates with gear 103 to rotate shaft 104 as shown in Figs. 1 and 3. Shaft 105 is connected to shaft 104 (Fig. 3) by a universal joint 106. Shafts 104 and 105 are rotatably supported by brackets 107 along beam 2, and connect to a clutch at each side of the machine (indicated 113, Fig. 2).

The purpose of the clutches 113 is to provide a means by which to steer and turn the machine by disengaging actuation on one side while the other side continues actuation. Details of the clutch are shown in Fig. 24, in which member 108 is secured to shaft 104 by set screw 109. Member 110 is arranged to rotate with member 108 by means of key 111 which is adapted to permit longitudinal motion of member 110 relative to 108. A lining 112 suitable for frictional contact is fixed to member 110. Member 113 which is adapted to cooperate with lining 112 is rotatably journaled on shaft 104 and maintained in position by collar 114. Spring 115 is arranged in compression between members 110 and 108 to maintain frictional contact between members 112 and 113 except when control is disengaged by application of force through control yoke 116 to compress spring 115. Rollers 117 are provided on each side of control 116 to cooperate with the flange portion of member 110 when the force is applied. Control yoke 116 is operated by a diaphragm power device 118 which is actuated by pressurized fluid introduced at passage 119. Sprocket 120, an integral portion of member 113, is provided to actuate drive chain 18, Fig. 2. Support 122 is fixed to brace member 15, and part 123 is secured to support 122 by bolts 124 to form a split bearing and rotatably support member 114.

Hydraulic fluid is supplied under pressure for operating device 118 of the clutches, Fig. 24, and to maintain front wheel piston 21, Fig. 21, in a predetermined position. No hydraulic fluid supply facilities are shown by the drawings, however any arrangement of conventional type may be applied.

An hydraulic fluid control valve for clutch members 108 is shown in Figs. 19, 20 and 21. A

casing 125 is provided with an inlet fluid passage 126, a return passage 127, and passage 128 which is connected to passage 119 of one clutch, Fig. 24, by a suitable fluid conduit, and passage 129 which is similarly connected to the other clutch. An oscillatory valve member 130 (Fig. 19), is fixed to shaft 131 which is journaled in cover member 132 and casing 125 which latter is provided with packing 133. Passages 134, 135 and 136 in valve 130 are arranged so that when the valve is oscillated counter clockwise, Fig. 19, pressurized fluid flows through passage 126, 135 and 128 to passage 119 (Fig. 24) of the clutch on the left side of the machine, while passage 119 on the other clutch is connected to the return line through passages 129, 134 and 127. When valve 130 is oscillated clockwise (Fig. 19) passages 128 and 129 are reverse in function, 128 being in the return circuit and 129 the pressurized circuit.

An arm 137, Figs. 20 and 21, is fixed to shaft 134 and connected by control link 138 to guide arm 139 which is fulcrumed to one end of member 140 which is fixed to the machine at the other end, as shown in Fig. 21. The purpose of this arrangement is to provide a means to steer the machine automatically by guide wheel 141 of guide arm 139, following a guide line arranged along the work, and thus causing valve 130 to function as the machine deviates from the course determined by the guide line to disengage the clutch and drive wheel 11 on the applicable side so that the other drive wheel 14 propels the machine about the disengaged wheel 11 as a pivot until the machine is brought to a true course. It is advantageous to adapt this control valve to operate on either side of the machine, at option, and also to provide a manual means of control. Guide arm 139 and member 140 also serve to maintain the machine on a predetermined grade as described hereinafter.

The extent of travel of the carriage member actuated by cable 46 along the span structure is controlled by means adapted to shift clutch member 82, Fig. 17, and thus reverse the travel direction of the carriage frame at a predetermined point on each side of the machine. This is accomplished by lever 142, Fig. 1, fulcrumed on supports 143, Fig. 5, which are fixed to cross members 144, Fig. 1, of the span structure. Lever 142 is connected at its upper end to control lever 85, Figs. 1 and 18, and to a rod indicated at 146, in Figs. 3 and 5 at its lower end by coupling 147 as shown in Figs. 1 and 3. Rod 146 is supported on the span structure by supports 148 adapted to permit free longitudinal motion of the rod. A contact member 149 is fixed at some predetermined point on each end of rod 146 by screw 150 and is adapted to shift clutch member 82 (Fig. 18) through rod 146, arm 142 and lever 85 when actuated by contact of carriage frame member 34 with member 149.

The members supported by the carriage frame for the purpose of performing construction operations, as shown in Fig. 1, from the front to the back, are: a combined leveling and mixer member, a scarifier member, a blade member, a vibrating roller and associated leveling member, and a roller member. These members are proportioned in size such that each covers about the same width of work. The travel of the members is practically transverse to the general strip of work. In the usual procedure of operation, the machine travels along the work a distance equal to the width of the work covered by the

individual operational member while the carriage frame passes from and returns to one side of the machine. Gears 102 and 103 (Fig. 1) are replaceable by sets of gears in various transmission ratios which in conjunction with the gear box ratios are applied to coordinate the rate of speed of the carriage frame with that of the entire machine for various specific operating conditions. The operational members of the machine are designed so that any of them may be prevented from operation while the others function, and any combination of the members may be used as are applicable.

The patentable features of the various operational members will be made the subject matter of separate patent applications and therefore the members will be described in only sufficient detail to reveal the general nature of some of the members which may be advantageously used with the machine set forth.

The combination leveling and mixer member is shown in Figs. 6 and 7. The mixing rotor 151, Fig. 6, is secured to shaft 152 by nut 153 for horizontal rotation. The mixer is adapted to discharge a fluid to material through openings 154. Mixer shaft 152 is rotatably supported by bearing 156 in housing 157 which is disposed in a housing 158 to permit vertical motion of 157 to adjust the depth of operation. Packings 159 and 160 are provided to seal the lubricant. A cover comprised of parts 161 and 162 are secured by bolts 163 (Fig. 7) to protect the parts from abrasive materials. A bracket 164 is attached to cover 161 and threaded to crank operated screw 165 with anti-thrust collar 166 to control depth setting. A gear 167 supported by bearings 168 is slidably fitted to mixer shaft 152 to rotate the mixer. A cover 169 is secured to casing 158 by bolts 110 and is adapted with packing 171 to seal mixer shaft 152. Fitting 172 for connection of a fluid supply line comprises non-rotating packing members 173 and 174, and retaining flanges 175 and 176 with packing 171 which rotates with shaft 152. A fluid line support 178 is provided.

A material retaining hood over the mixer comprises side members 179 and 180 fixed to supports 181 from the carriage frame by bolts 182, and top 183 being secured by bolts 184, Figs. 6 and 7. Leveling members 185 (Fig. 7) are pivotally supported by brackets 186 secured to the hood by bolts 187 positioned by stop screws 118, fixed to the hood. The mixer is actuated by power plant 190 through clutch 191, through gear 192 and shaft 193 supported by case 194 and bearing 195, cooperating with gear 196 and shaft 197 supported by bearings 198 and 199. Gears 200, 201, 202 and control lever 203, control shaft 204, arm 205, yoke bearing 206 (Figs. 6 and 7) and are arranged to permit two different transmission drive speed ratios for the mixer.

A two speed power take off for actuating a vibrating roller is shown in Figs. 6 and 7, comprising shaft 207, gears 208 and 209, control lever 210, with shaft 211 and arm 212.

Fluid cement, asphalt or other agent is conveyed to the mixer through flexible conduit 213 (Fig. 1) connected to fitting 172 and supported by link 214 and clamp 215. To support the other end of the fluid conduit a reel is provided (Fig. 16) in which drum 217 is rotatably supported by hollow shaft 218 journaled upon the span structure by bracket 216. Fitting 219 provided with packing 220 about shaft 218 is secured to drum 217 by bolts 221 and 222 and serves to convey fluid from shaft 218 to flexible conduit 75

213. Slack of conduit 213 is maintained wound upon drum 217 by torque applied by spring 223 (Fig. 16) fixed to shaft 218 and bearing part 225 by pin 224 at one end, and to drum 217 by bolt 221 at the other end. A fluid supply source may be mounted on the machine and connected by fitting 226 to hollow shaft 218.

The scarifier member is shown in Figs. 1, 6, 7 and 14. Scarifier teeth 227 are secured to frame 228 by pins 229 (Fig. 7). Guide members 230 (Figs. 6 and 14) extended from the carriage frame, cooperate with lugs 231 of frame 228 to permit vertical movement of the frame on members 230. Four control screws 232 (Figs. 7 and 14) rotatably supported on the carriage frame by parts 233 cooperate with lugs 231 by threads to permit vertical control of the scarifier.

The blade member comprises two blades pivotally supported in opposed relation as illustrated in Figs. 1, 6, 11 and 15. Mold board 234 (Fig. 15) with affixed bits 235 is pivotally supported by shaft 236 upon bearings 237 secured to side plates 238 and 239 provided with stiffeners 240 secured by bolts 241. Side plates 238 and 239 for the purpose of retaining material on the blades are fixed to frame members 242 and 243 (Fig. 15) which are provided with stop screws 245 adapted to limit the pivot arc and angle of the blade members by contact with parts 246. Fixed to the end of frame members 247, (Fig. 15) are lugs 248 threaded for cooperation with vertical adjustment screws 249. Guide members 250 fixed to frame members 242, 243 and 248 extend vertically and slidably through guides 251 fixed to carriage members 25. Screws 249 are rotatably supported on the carriage frame 25 by screw housings 252 and brackets 253 (Fig. 15).

The vibrating roller and associated leveling members are shown in Figs. 11 and 12. Roller cylinder 254 (Fig. 11) is fixed to end 255 rotatably supported on hollow shaft 256, and end 257 secured to cylinder 254 by bolts 258 is rotatably supported on shaft 259 (Fig. 11). A shaft 260 with eccentrically attached weight 261 is rotatably supported by hollow shaft 256 and bearing 262 and is provided with gear 263 adapted to cooperate with a similar gear 264 fixed to a shaft 265 with eccentrically attached weight 266. Shaft 265 is rotatably supported by bearing 267 mounted in member 268 fixed to a non-rotating shaft 259. A screw 269 secures thrust bearing 270 to shaft 265. Three frame members 271 (Fig. 11) fixed to member 268 extended radially within the roller to join three similar frame members 273 which are fixed to hollow shaft 256 (Fig. 11). Shaft 260 is connected through universal joint 276 and shaft 207 (Fig. 6) for rotative actuation. Roller support shafts 256 and 259 are fixed to roller frame members 277 and 278 by parts 279 and 280 (Fig. 11). These frame members are joined by end members 281 and 282; and the frame unit is pivotally supported about shaft 283 (Fig. 12) which is secured to carriage member 25 by brackets 284 (Fig. 11).

Compression spring 285 (Fig. 12) is arranged between roller frame member 281 and cap 286, threaded to adjusting screw 287 which bears on bracket 288 through thrust washer 289 at the upper end of the screw. The lower end of screw 287 is retained by support 290 secured to carriage member 25 by bolts 291 (Fig. 12). An adjusting screw eye 292 is provided for turning, and a stop nut 293 is provided on the screw to set the roller frame supported upwardly out of operative position.

The pressure of the roller 254 is predetermined by setting the compression spring 285. Vibration is provided by the centrifugal force of weights 261 and 266, (Fig. 11) occurring in unison at the upper and lower points of the respective rotation orbits.

The leveling member associated with the roller 254 is illustrated in Fig. 12, and comprises a rectangular frame 294, vertical supports 295, diagonal braces 296 and 297, and end cross braces 298 (Figs. 1 and 12). Vertical supports 295 are slidably retained by guide brackets 299 fixed to carriage members 25, and frame 294 is set in a predetermined position by cooperative control screws 300 rotatably fixed to carriage members 25 by parts 301. Similar and opposed leveling mold boards 302 are pivotally supported to each end of frame 294 by bearings 303, and have blades 304 fixed thereto by brackets 305. Screws 306 (Fig. 12) of frame 294 function to limit and predetermine the pivotal arc of mold board 302. End plates 307 secured to frame 294 by bolts 308 are provided to retain material. Leveling is accomplished by blade 304 of the mold board 302, which trails in operation travel, functioning to loosen material which is leveled by passing under the mold board.

The final roller member 309 is similar to the roller hereinabove described except it is not arranged for vibration.

An automatic hydraulic means, for controlling the grade at which the machine operates by regulating the height of girders 10 above front wheels 19 through piston 21 (Figs. 1 and 21), is provided. Rear wheels 11 travel on the completed surface in most applications.

An hydraulic control valve for elevation control comprises casing 310 with a detachable top 311 (Figs. 21, 22 and 23) contains float 312 connected by arm 313 to shaft 314 which is connected by arm 315 (Fig. 22) which cooperates with pin 316 (Fig. 23). Through pin 316 (Fig. 22) and arm 317, a rotary valve 318, fixed to shaft 319, is pivoted in operative range. Passage 320 is connected by a fluid line to a pressurized fluid source, passage 321 to wheel cylinder 22, and passage 322 to a low pressure return line as illustrated in Fig. 23. The above valve functions to introduce or to return hydraulic fluid from wheel cylinder 22. The control valves are slideable vertically on guide 325 by cooperation with screws 325 which bears on girder 10 by part 326 (Figs. 1 and 21). Screw 325 is operated by pulleys 327 and 328 coupled by cable 329 (Fig. 1). The control valve casings 310 are connected at passages 330 (Fig. 23) of a fluid line, a portion of which is shown as 331 (Fig. 5) and a fluid reservoir 332 is connected to line 331 by flexible fluid conveying line 333 through valve 334 (Figs. 1 and 5). Fluid reservoir 332 is shifted vertically on guide 335 fixed to span structure portion 6, by screws 336 (Figs. 1 and 5). Grade control is accomplished by the fluid maintaining a common level in the valve casings and reservoir 332 by gravity flow through the interconnecting fluid conveying lines, the valve being actuated by a change in fluid level to cause hydraulic shifting of piston 21 (Fig. 1) in a direction to tend to maintain a predetermined level of fluid in the valve casings.

The machine may be controlled by a wire or other suitable means placed on a predetermined grade line to guide wheel 141 (Fig. 21) and thus actuate valve 318 through arm 139, member 140, and link 338 connected to pin 316 (Fig. 23).

To arrange the machine for convenient trans-

portation, the span structure is constructed with splice joints in beams 1 and 2 about eight feet from one end adapted so that the structure may be separated at the joints. The carriage frame 5 assembly and both sets of wheels with girders 10 are arranged in usual orientation on the short part of the span structure and the remaining longer part of the structure is placed on top of and parallel with wheel girders 10. Rear wheels 11 (Figs. 2 and 4) are provided with lugs 339 adapted to secure an auxiliary wheel with a pneumatic tire of sufficient diameter to keep wheel 11 off of road surfaces while the machine is in transit. The front wheels are made free for turns by disengaging link 23 and bracket 24 (Fig. 1).

The splices for the knock-down joints in the span structure referred to above are shown in Fig. 11. Beams 1 and 2 and rails 39 have right angle butt joints secured by splice plates 340 and 341 fixed to the webs and flanges of the beams by bolts 342, and dowels are placed through rail joints 39. Span structure braces 4 at the splice may be made detachable, but preferably are arranged such that none connect between the two parts of the span structure, as separated by the joints.

The foregoing description and related drawings have illustrated one embodiment of my invention. Modifications in the construction of the machine 30 may be made within the scope of the claims.

The operation of the machine is as follows:

The construction of a flexible base, sub grade, of courses stabilized with cement, bitumen, salt, or the like, and other courses which require mixing, addition of water or stabilizing material, leveling and compacting to a defined section, are all handled in the same general manner.

The material to be worked is uniformly windrowed in the middle, or evenly distributed over the work strip. The wheels which support the machine are set to travel on the outer parts of the work strip, and the machine is adjusted to operate to the desired width. Leveling members 185 are adjusted in elevation to level the material and above any surplus to the edges; and mixed rotor 151 is set to operate at a predetermined depth; and the required quantity of moisture or stabilizing material in fluid condition is introduced through the rotor 151 as set forth. 50 The scarifier 227 need not be operated unless additional mixing is desired.

Blade members 235 (Figs. 1 and 15) are set at proper elevations and pitch angles by means previously described so that an appreciable quantity 55 of material is carried back and forth across the work between the two blade members. The leading blade revolves to the extent that the material does not accumulate in front of it, but accumulates in front of the trailing blade. This 60 evenly distributes the material and compacts it to an extent, depending on the quantity of material shifted between the blades.

The vibrating roller 254 (Fig. 11) is set at the desired pressure by spring 285 (Fig. 12) and appropriate centrifugal weights 266 and 261 are rotated at a rate to obtain the desired amplitude and frequency in the roller vibration. The leveling members 302, 304, etc. Fig. 12, which are associated with the vibrating roller, in the case of most materials, are adjusted so that they loosen the material only to the depth necessary to include the lower spots left by the roller, and maintain sufficient surplus on the mold board of the functioning member to leave the material in a

uniform condition by means set forth suitable for final rolling.

When the carriage travel is reversed, direction at the edge of the work, the surplus material is crossed by the roller and picked up by the other leveling member.

Minor modifications in the construction of the vibrating roller and associated leveling member may be made to most effectively adapt the machine to the material under operation. The final roller is generally set at a predetermined pressure controlled by the spring as described.

The machine is obviously more applicable to construction with materials which may be compacted immediately after mixing. However, when a curing period is desired before compaction the rolling operations may be omitted from the first passage and performed during the second passage.

When the machine is applied to construction of ready mixed materials such as concrete, bituminous concrete, or any material not requiring mixing, the operations are substantially the same as described above, except that the mixer rotor is inactive and raised in position.

To cut trench subgrade, to terrace and grade, the scarifier member may be operated to loosen the material to the desired depth. The blades may be set to shove the surplus material to the edges, one member shoving part of it to one side and the other member shoving the balance to the other side, or both blade members may be set to shove it to the same side. The vibrating roller, associated leveling member and final roller may be operated as described above in connection with these operations.

As mentioned hereinbefore, the usual operative speed of the machine as a whole, relative to the crosswise travel speed of the carriage assembly, is such that the carriage travels from one side of the work to the other and returns while the machine travels a distance equal to the width of work covered by one of the individual operation members. When operated at this ratio the work is covered twice by the same operation and the passes overlap one another, which is very advantageous in obtaining a uniform and thoroughly worked section. In case of some materials which are difficult to handle the forward travel rate may be relatively reduced to give additional passes of the same operations over the material.

It is possible to operate the machine on material against a curb, or along the trimmed edge of other work as applicable in construction of a wider section than can be covered in one work strip. In such application the various operation members lap over the edge of the curb or work being joined, and the surplus material deposited thereon ahead of the vibrating roller serves to protect the curb or work being joined from direct impact of the roller. Surplus material is removed from the curb or work surface by the leveling member following the vibrating roller. The application just described is without use of the mixer rotor and the scarifier member which would obviously interfere with the curb or work being joined in most cases, if lowered for operation.

The above description and drawings are merely an illustration of my invention in one of many possible forms of application, and the scope of protection contemplated is to be taken from the appended claims interpreted as broadly as is consistent with the prior art.

I claim:

1. A road machine, comprising a wheel supported frame structure; a trackway supported by said frame structure transversely of the longitudinal axis thereof; a carriage supported by rollers on said trackway for back-and-forth movement thereacross; road working elements supported by said carriage; power means mounted on said frame to propel the machine; means operated by said power means to actuate the carriage back-and-forth on said trackway; said trackway comprising hinged sections; and means to adjust said hinged sections relative to each other to conform with a desired road crown curvature whereby movement of the carriage will conform therewith.

2. In a machine as set forth in claim 1, said hinge section adjusting means comprising a shaft offset from and journaled parallel with said hinge of the sections; said shaft being provided with eccentric portions cooperating with bearing members connected to the respective sections to pivot the sections about said hinge when the shaft is rotated; and means for rotating said shaft into, and locking said shaft in adjusted positions.

3. In a machine as set forth in claim 1, said carriage actuating means comprising a drum; a cable coiled around said drum and having its ends secured to opposite ends of the carriage; reversible means operated by said power means for rotating the drum; and means adapted to be engaged by the carriage when nearing the limits of its movement in either direction to cause reversal of rotation of the drum.

4. A road machine, comprising a wheel supported frame structure; a trackway supported by said frame structure transversely of the longitudinal axis thereof; a carriage supported by means of rollers on said trackway for back-and-forth movement; said carriage comprising a main frame pivotally supported about a vertical axis on an intermediate frame which is supported by said rollers on the trackway; road working elements supported by said carriage; power means mounted on said frame to propel the machine; means operated by said power means to actuate the carriage back-and-forth on said trackway; said trackway comprising hinged sections; means to adjust said hinged sections relative to each other to conform with a desired crown curvature, whereby movement of the carriage will conform therewith.

5. In a machine as set forth in claim 4, said hinge section adjusting means comprising a shaft offset from and journaled parallel with said hinge of the sections, said shaft being provided with eccentric portions cooperating with bearing members connected to the respective sections to pivot the sections about said hinge when the shaft is rotated; and means for rotating said shaft into, and locking said shaft in adjusted positions.

6. In a machine as set forth in claim 4, said carriage actuating means comprising a drum; a cable coiled around said drum and having its ends secured to opposite ends of the carriage; reversible means operated by said power means for rotating the drum; and means adapted to be engaged by the carriage when nearing the limits of its movement in either direction to cause reversal of rotation of the drum.

7. In a machine as set forth in claim 4, means on the carriage main frame and intermediate frame for predetermining the extent of the arc

within which the carriage main frame may swing on the intermediate frame.

8. In a machine as set forth in claim 4, means on the carriage main frame and intermediate frame for predetermining the extent of the arc within which the carriage main frame may swing on the intermediate frame; and means for causing the carriage main frame to retain a position at one extreme of said arc by a drag force while the carriage is moving in one direction across the trackway, and means whereby when the direction of travel of the carriage is reversed the carriage main frame will swing to the opposite extreme of said arc.

9. A road machine, comprising a wheel supported frame structure; a trackway supported by said frame structure transversely of the longitudinal axis thereof; a carriage supported by means of rollers on said trackway for back-and-forth movement thereacross; road working elements supported by said carriage; power means mounted on said frame to propel the machine; means operated by said power means to actuate the carriage back-and-forth on said trackway; said trackway comprising hinged sections; and means to adjust said hinged sections relative to each other to conform with a desired road crown curvature, whereby movement of the carriage will conform therewith; said trackway having a short section supported on said frame structure, and a long section adapted to be swung into superimposed position on said short section parallel with the longitudinal axis of the machine to facilitate transportation of the machine.

10. In a machine as set forth in claim 9, said hinge section adjusting means comprising a shaft offset from and journaled parallel with said hinge of the sections; said shaft being provided with eccentric portions cooperating with bearing members connected to the respective sections to pivot the sections about said hinge when the shaft is rotated; and means for rotating said shaft into, and locking said shaft in adjusted positions.

11. In a machine as set forth in claim 9, said carriage actuating means comprising a drum; a cable coiled around said drum and having its ends secured to opposite ends of the carriage; reversible means operated by said power means for rotating the drum; and means adapted to be engaged by the carriage when nearing the limits of its movement in either direction to cause reversal of rotation of the drum.

12. In a machine as set forth in claim 9, said carriage comprising a main frame pivotally supported about a vertical axis on an intermediate frame which is supported by said rollers on the trackway.

13. In a machine as set forth in claim 9, said carriage comprising a main frame pivotally sup-

ported about a vertical axis on an intermediate frame which is supported by said rollers on the trackway, and means on the carriage main frame and intermediate frame for predetermining the extent of the arc within which the carriage main frame may swing on the intermediate frame.

14. In a machine as set forth in claim 9, said carriage comprising a main frame pivotally supported about a vertical axis on an intermediate frame which is supported by said rollers on the trackway, and means on the carriage main frame and intermediate frame for predetermining the extent of the arc within which the carriage main frame may swing on the intermediate frame, and means for causing the carriage main frame to retain a position at one extreme of said arc by a drag force while the carriage is moving in one direction across the trackway, and means whereby when the direction of travel of the carriage is reversed the carriage main frame will swing to the opposite extreme of said arc.
